UNITED STATES PATENT OFFICE.

HANS BAUMEISTER, OF STUTTGART, WILHELM E. DÖRR, OF FRIEDRICHSHAFEN, BODENSEE, GERMANY, AND KARL HÜRTLE, OF AKRON, OHIO, ASSIGNEES TO LUFTSCHIFFBAU ZEPPELIN GESELLSCHAFT MIT BESCHRÄNKTER HAFTUNG, OF FRIEDRICHSHAFEN, GERMANY.

GAS-INFLATED AIRSHIP.

Application filed July 13, 1926, Serial No. 122,122, and in Germany August 3, 1925.

Our invention relates to gas-inflated airships and more especially to the envelopes of such ships.

An object of our invention is to provide for a constant gas temperature or at least to reduce the fluctuation in gas temperature as far as possible. Such fluctuations cause changes in lift of the airship and should therefore be omitted with regard to better operation in vertical direction.

It is known to make the outer surface of such ships brilliant so that sun rays will be reflected. This will prevent to a certain extent the gas from becoming warmer than the surrounding air. But if the sun shines on the ship for a longer time the gas still will gain a certain degree of overtemperature, which temperature will vanish shortly after the sun has ceased to shine on the ship.

Thus the lift of the ship will instantly be reduced.

According to our invention we are reducing or totally doing away with this drawback by providing means for preventing the heat in the gas from dissipating. This for example may be attained by providing a brilliant surface on the inside of the gas envelope. Thus, according to our invention the inside surface of the gas bag is made brilliant so as to reflect all heat rays and prevent them from dissipation.

This means will be of good effect if used alone as it will prevent or reduce heat dissipation from the gas into the atmosphere, so that in case of the gas having attained over-temperature by whatever circumstances this temperature will be kept constantly or at least be diminished very slowly only.

With rigid airships having an outer cover and an inner gas envelope the effect will still be greater, because both, the outer cover and the inner gas envelope, according to our invention, may be provided with brilliant inner surfaces.

A further improvement may be attained by combining our invention of brilliant inner surfaces with the above described known method of making the outer surface brilliant. Thus heat will be prevented from entering the gas envelope and it will also be prevented from being withdrawn from the gas. In this way the fluctuations of the

gas temperature will be reduced to a minimum.

With rigid airships the effect may be doubled, so to say, because of the possibility of providing two outer brilliant surfaces and two inner brilliant surfaces. Of course, according to the prevailing circumstances, it may be preferable to provide only two or three brilliant surfaces, because the material necessary for rendering the surfaces brilliant will afford a certain weight and thereby the disposable lift of the airship will be reduced. Such brilliant or reflecting material may be for instance a layer of aluminum powder applied to the varnish on the envelope before becoming dry.

Having given a general description of our invention we now want to point it out more in detail referring to the drawing representing an example embodying our invention.

The figure is a diagrammatic vertical cross section through a rigid airship of the Zeppelin type. The longitudinal girders 1 confine the gas space 10. The gas envelope 2 has an outer brilliant lining 5 and an inner brilliant lining 4. The outer cover 3 of the airship also has an inner brilliant lining 6 and an outer brilliant lining 7.

We do not want to limit ourselves to the details described or shown in the drawings as many variations will occur to those skilled in the art.

What we claim is.

1. An airship comprising a bag inflated with gas; the envelope of said bag having a brilliant inner surface adapted to reflect heat rays.

2. An airship comprising a bag inflated with gas; the envelope of said bag having a brilliant inner surface and a brilliant outer surface; said surfaces being adapted to reflect heat rays.

3. An airship comprising a bag inflated with gas; and an outer cover distanced from the walls of said bag; the inside surfaces of said walls of said bag being brilliant and adapted to reflect heat rays.

4. An airship comprising a bag inflated with gas; and an outer cover distanced from the walls of said bag; the inside and the outside surfaces of said walls of said

bag being brilliant and adapted to reflect heat rays.

5. An airship comprising a bag inflated with gas; and an outer cover distanced from the walls of said bag; the inside surfaces of said walls of said bags and the inside surface of said outer cover being brilliant and adapted to reflect heat rays.

6. An airship comprising a bag inflated with gas; and an outer cover distanced from the walls of said bag; the inside surfaces of said walls of said bags and the outside surface of said outer cover being brilliant and adapted to reflect heat rays.

15 7. An airship comprising a bag inflated with gas; and an outer cover distanced from the walls of said bag; the outside surfaces of said walls of said bags and the inside surface of said outer cover being brilliant and adapted to reflect heat rays.

8. An airship comprising a bag inflated with gas; and an outer cover distanced

from the walls of said bag; the inside and the outside surfaces of said walls of said bag and the inside surface of said outer cover being brilliant and adapted to reflect heat rays.

9. An airship comprising a bag inflated with gas; and an outer cover distanced from the walls of said bag; the inside and the outside surfaces of said walls of said bag and the outside surface of said outer cover being brilliant and adapted to reflect heat rays.

10. An airship comprising a bag inflated with gas; and an outer cover distanced from the walls of said bag; the inside and the outside surfaces of said walls of said bag and of said outer cover being brilliant and adapted to reflect heat rays.
